UNITED STATES PATENT OFFICE

ALWIN G. STEINMAYER, OF MILWAUKEE, WISCONSIN, ASSIGNOR, BY MESNE ASSIGNMENTS, TO LINE MATERIAL COMPANY, OF SOUTH MILWAUKEE, WISCONSIN, A CORPORATION OF DELAWARE

BUS SUPPORT

Application filed February 15, 1926. Serial No. 88,468.

This invention relates to certain new and useful improvements in bus supports and more particularly to that type of bus support especially designed for use in handling voltages of 2300 volts or less.

Heretofore, on 2300 volt service it has been necessary to use supports suitable for 6600 or 7500 volts due to the fact that the effective clearance between the metal securing members on each end of the porcelain has been considerably less than the height of the porcelain. These securing members consisted of flanged thimbles cemented into recesses in both ends of the porcelain and it is evident that to obtain the proper mechanical strength it was necessary that thimbles be comparatively long thus greatly increasing the height of the porcelain and consequently the cost thereof, and, therefore, it is an object of this invention to provide a bus support which has its porcelain relatively shortened without any loss in efficiency.

Another object of this invention resides in the provision of means for securing the hardware thereto whereby the porcelain is held in compression at all times thus increasing its ability to withstand all normal working stresses.

A further object of this invention resides in the provision of a bus support having its porcelain member bored and its hardware secured thereto by bolts passed through the bores in the porcelain thereby making the support readily adaptable to use with any of the various styles of hardware common to the art to which this invention belongs.

A still further object of this invention resides in the production of a bus support at a relatively low cost and in which all assembling of parts with cement is eliminated.

With the above and other objects in view which will appear as the description proceeds, my invention resides in the novel construction, combination and arrangement of parts substantially as hereinafter described and more particularly defined by the appended claims, it being understood that such changes in the precise embodiment of the herein disclosed invention may be made as come within the scope of the claims.

In the accompanying drawing, I have illustrated one complete example of the physical embodiment of my invention constructed according to the best mode I have so far devised for the practical application of the 55 principles thereof, and in which:

Figure 1 is a perspective view of a bus support embodying my invention;

Figure 2 is a sectional view taken through Figure 1 on the plane of the line 2—2; and 60

Figure 3 is a cross sectional view taken through Figure 2 on the plane of the line 3—3.

Referring now more particularly to the accompanying drawing in which like numerals 65 designate like parts throughout the several views, the numeral 5 designates a bus bar which is supported from a mounting member 6 by a bus support 7. While in the drawing the member 6 has been shown as a pipe, it is 70 understood that various shapes and forms of mounting members may be employed.

The support 7 consists of an insulating member 8 of porcelain or other non-conducting material, having a flat top 9 and a flat 75 bottom 10. The porcelain member also has a pair of diametrically opposed bores 11 counter-bored from the bottom 10, as at 12, and a pair of diametrically opposed bores 13 counter-bored from the top 9 of the porcelain 80 member, as at 14, and so arranged that lines drawn through the center of the pairs of bores will intersect at the axis of the member 8 at right angles to each other.

The porcelain member is supported above 85 the member 6 by a base member 15 which may be suitably secured thereto by a clamping device or other means 15', and has an upper annular flange 16 provided with a pair of diametrically opposed arcuate slots 17. A 90 centrally located boss 18 projects above the top face of flange 16 and is received within a recess 19 in the bottom 10 of the porcelain. The boss 18 provides a pivot about which the porcelain may be rotated, and the arcuate 95 slots 17 are so arranged to radially align the bores 13 therewith. Securing bolts 20 are passed through the bores 13 with their heads anchored in the counterbores 14 and extend down through the arcuate slots 17 to adjust- 100

ably secure the porcelain to the base member 15. Thus it will be seen that the porcelain member is rotatably adjustable on the base member through approximately ninety degrees.

5 In the present embodiment I have shown the bus bar 5 secured to the porcelain by two complementary L-shaped members 21 known in the art as the tongue type hardware, although any of the various types of hardware 10 may be employed, as the means for mounting or securing the bar to the porcelain is common to all types. In this instance the short legs 22 of members 21 are apertured to receive 15 securing bolts 23 passed through the porcelain bores 11 with their heads anchored in the counter-bores 12. The long or vertical legs 24 of the members 21 are provided with a plurality of registering apertures 25 spaced 20 at different distances from the top of the porcelain, to accommodate bus bars of various heights. The legs 24 are spaced a distance substantially equal to the width or thickness of the bus bar and rigidly clamp the same 25 therebetween, being drawn together by a clamping bolt 26.

If desired the counter-bores 12 and 14 may be filled after assembly, with a suitable plastic insulating compound, as shown in Figure 2 30 by the dotted cross hatching 27. In so doing, cutting down the electrical flash-over of the assembled unit, by the filling of the counter-bores with dust, dirt or moisture, is entirely 35 eliminated.

35 The construction described eliminates the various stresses which accompany bus supports of the old style in which the porcelain is deeply recessed at both ends to accommodate the thimbles of the hardware. As will 40 be readily obvious the securing bolts 20 and 23 tend to create opposed stresses within the porcelain itself thereby putting the same entirely in compression at all times. In addition, my invention reduces the overall height 45 of the support, permitting its use in cramped quarters.

What I claim as my invention is:

1. A device of the class described, comprising a base member, a flange on the base member 50 having arcuate slots therein, a centrally disposed lug projected from the base member, an insulating member adapted to support a conductor and having a recess adapted to receive the lug, said insulating member being 55 adjustable about the lug, and securing means passed through the insulating member and the arcuate slots to adjustably secure the same to the flange.

2. A device of the character described, comprising a base member having a flat top face, a pivot boss centrally projecting above the top surface of the base member, an insulating member having a flat bottom surface with a central pivot recess whereby the abutting 65 faces of said members substantially conform,

said insulating member having a plurality of bores counter-bored from the top and a plurality of bores counter-bored from the bottom, electrical means adapted to be supported from the top of said insulator member, securing 70 means passed through the first-mentioned bores and through arcuate slots in the base member struck on an arc having the axis of the pivot boss as a center to adjustably secure the insulating member to the base member, 75 and means passing through the second-mentioned bores to secure the electrical means to the insulating member.

In testimony whereof I affix my signature.

ALWIN G. STEINMAYER.
